UNITED STATES PATENT OFFICE.

CHARLES RUBEN, OF PITTSBURGH, PENNSYLVANIA, ASSIGNOR OF ONE-HALF TO
JACOB A. RUBEN, OF PITTSBURGH, PENNSYLVANIA.

NECKTIE.

1,159,099.

Specification of Letters Patent.

Patented Nov. 2, 1915.

Application filed November 5, 1914. Serial No. 870,372.

To all whom it may concern:

Be it known that I, CHARLES RUBEN, a citizen of the United States of America, residing at Pittsburgh, in the county of Allegheny and State of Pennsylvania, have invented certain new and useful Improvements in Neckties, of which the following is a specification, reference being had therein to the accompanying drawing.

10 This invention relates to neck ties and has for its object to provide a neck portion of a tie, with means in a manner as hereinafter set forth, to facilitate the shifting of said neck portion, in a collar when positioning 15 the tie for the purpose of tying a bow, or otherwise to provide the neck portion of a tie with means to prevent the binding or wedging of said neck portion in a collar when it is desired to shift the neck portion 20 for the purpose of tying a bow.

Further objects of the invention are to provide a neck tie for the purpose set forth which is simple in its construction and arrangement, strong, durable, efficient in its 25 use and inexpensive.

With the foregoing and other objects in view the invention consists of the novel construction, combination and arrangement of parts as hereinafter more specifically 30 described and illustrated in the accompanying drawing wherein is shown an embodiment of the invention, but it is to be understood that changes, variations and modifications can be resorted to which come within the 35 scope of the claims hereunto appended.

In the drawings wherein like reference characters denote corresponding parts throughout the several views:—Figure 1 is a perspective view of a neck tie, showing the 40 adaptation therewith of means to prevent the binding or wedging of the neck portion thereof, in accordance with this invention. Fig. 2 is a section on the line X X Fig. 1.

Referring to the drawings in detail 1 45 notes the neck portion of a tie and 2, 3, the end portions. Arranged against the outer side of the neck portion 1, is a rectangular strip 4 of flexible material, preferably celluloid, and overlapping said neck portion 1, 50 as well as the strip 4, is a retaining member 5, formed of flexible material, preferably

celluloid, and of less thickness than the strip 4. The strip 4, as well as the retaining member 5, is pressed upon the neck portion 1, whereby the strip and retaining member 55 will adhere together and the retaining member will adhere to the neck portion 1. Under such conditions the strip 4 and retaining member 5 are fixedly secured to the neck portion 1. The neck portion 1 is formed 60 with an opening 6, which registers with the openings 7, 8, formed in the retaining member 5 and with the opening 9 formed in the strip 4.

Arranged between the folds of the neck portion 1 and extending transversely with respect thereto, is a pin 10, and the latter is maintained in position by the bend 12 of the member 5. Rotatably carried by the pin 10 is an anti-friction roller 13, of a diameter 70 to project from the openings 7, 8, and capable of riding against the folds of a collar to prevent the neck portion 1 from binding or wedging when the latter is shifted to position the tie for the purpose of forming 75 a bow.

The strip 4 reinforces the neck portion 1, at the point where the opening 6 is formed and said neck portion is also reinforced by the retaining member 5.

As the strip 4 and retaining member 5 are very thin, it is obvious that the part of the neck portion 1, to which they are secured, will not be of such thickness as to cause a bulging of the collar.

What I claim is:—

1. The combination with a necktie having the neck portion thereof formed with an opening extending transversely of the folds thereof, of a pin arranged in said neck portion and projecting across the opening transversely of the tie, a rotatable anti-friction roller carried by the pin and arranged within the opening whereby said roller projects from opposite sides of the tie, and 90 means for retaining said pin in position.

2. The combination with a necktie having the neck portion thereof formed with an opening extending transversely of the folds thereof, of a pin arranged in said neck 100 portion and projecting across the opening transversely of the tie, a rotatable anti-fric-

tion roller carried by the pin and arranged within the opening whereby said roller projects from opposite sides of the tie, a yieldable reinforcing strip arranged upon one side of the neck portion and a U-shaped flexible retaining member engaged over the tie and strip to hold the pin and strip in position, said U-shaped member being provided

with openings for the projecting portions of the roller as and for the purpose set forth. 10

In testimony whereof I affix my signature in the presence of two witnesses.

CHARLES RUBEN.
